Primary Examiner — Kevin K Rudzinski*Assistant Examiner* — Paul D Bohannon(74) *Attorney, Agent, or Firm* — Garcia-Zamor IP Law;
Ruy M. Garcia-Zamor(57) **CLAIM**

The ornamental design for a boat chair, as shown and described.

DESCRIPTION

FIG. 1 is a top front perspective view of a boat chair according to the present invention;

FIG. 2 is a front side elevational view of the boat chair of FIG. 1;

FIG. 3 is a rear side elevational view of the boat chair of FIG. 1;

FIG. 4 is a left side elevational view of the boat chair of FIG. 1;

FIG. 5 is a right side elevational of the boat chair of FIG. 1;

FIG. 6 is a top plan view of the boat chair of FIG. 1;

FIG. 7 is a bottom plan view of the boat chair of FIG. 1;

FIG. 8 is a rear left bottom perspective view of the boat chair of FIG. 1; and,

FIG. 9 is rear right top perspective view of the boat chair of FIG. 1.

The broken lines in FIGS. 1-9 represent environment and are for illustrative purposes only and do not constitute part of the claimed design.

1 Claim, 7 Drawing Sheets(56)
